UTILITY BAG

Harvey M. Sherman and Harriet N. Sherman, both of 16838 Germain St., Granada Hills, Calif. 91344

Filed June 6, 1973, Ser. No. 367,472

Term of patent 14 years

Int. Cl. D9—05

U.S. CL. D9—251

FIG. 1 is a front elevational view of a utility bag showing our new design;

FIG. 2 is an edge view thereof taken in the direction of the arrows 2—2;

FIG. 3 is a rear view of the utility bag;

FIG. 4 is a bottom edge view taken in the direction of the arrows 4—4; and

FIG. 5 is a top edge view taken in the direction of the arrows 5—5.

We claim:

The ornamental design for a utility bag, as shown and described.
